KARL MELLER, OF SIEMENSSTADT, NEAR BERLIN, GERMANY, ASSIGNOR TO SIEMENS-SCHUCKERTWERKE GESELLSCHAFT MIT BESCHRANKTER HAFTUNG, OF SIEMENSSTADT, NEAR BERLIN, GERMANY, A CORPORATION OF GERMANY.

ELECTROMAGNETIC COUPLING.

Application filed June 21, 1921. Serial No. 479,318.

To all whom it may concern:

Be it known that I, KARL MELLER, a citizen of the German Empire, residing at Siemensstadt, near Berlin, Germany, have invented certain new and useful Improvements in Electromagnetic Couplings (for which I have filed applications in Germany December 12th, 1919; Austria April 21st, 1920; Great Britain June 5th, 1921; France March 10 22nd, 1921, and Belgium March 24th, 1921), of which the following is a specification.

My invention refers to electromagnetic couplings and its particular object is to facilitate the changing over of such couplings.

An essential requirement in the use of electromagnetic couplings, more especially those arranged in double for changing over from one direction of rotation to the other, is the 20 possibility of changing over the coupling as rapidly as ever possible and at the correct moment, without, however, endangering the transmission and coupling-gear.

The drawback, attaching to these couplings, in not changing over the coupling immediately after the electric switch has been changed over, is due to remanent magnetism, i. e. a certain time being required, until the magnetism in the cut-out portion 30 of the coupling has sufficiently diminished to allow the magnetic armature to drop, and also, until the magnetism in the cut-in portion of the coupling has sufficiently increased to attract the armature. In order to obtain 35 a rapid action of the coupling, it is necessary, therefore, to provide that the magnetism diminishes and increases, respectively, as quickly as possible. This can be effected by connecting a resistance of high value in

40 parallel and another one in series with each magnet coil. In this case, however, it is of importance, that the dropping of the armature by one and the attracting by the other half of the coupling take place simultaneously. In order to attain this, the resistances must be adjusted in a certain way with regard to one another as well as to the magnetic conditions of the coupling. It is, however, impossible in actual working, on 45 account of the wear at the friction surfaces of the coupling, to prevent the air-gap between armature and magnet from changing in the course of time. In this manner the magnetic conditions are changed in regard

to the increase and decrease of magnetization and the adjustment, previously effected, to the most favourable conditions for changing over is disturbed.

This drawback is avoided by designing the series-resistances as also those connected in parallel, not only in the form of so-called adjusting resistances, which only permit of an initial adjustment to the most favourable conditions, but also in the form of regulating resistances, by means of which it is possible to re-adjust from time to time to the best conditions for changing over, in case the conditions should have changed.

Regulating series-resistances have already been used in connection with magnetic couplings, such resistances however, fulfilling an entirely different purpose, since they are intended to vary the output of the coupling by increasing or decreasing the tractive effort. These arrangements are generally of much greater extent than that disclosed in the present invention, and no regard can of course be given in such arrangements to the maintenance of the most favourable conditions for changing over.

In the drawings attached to this specification and forming part thereof two couplings embodying my invention are illustrated diagrammatically by way of example. In these drawings—

Figure 1 represents a magnetic reversible coupling in which each of the two magnets is provided with an individual shunt resistance and both magnets have a joint series resistance; and

Figure 2 represents such a coupling in which each of the magnets has its individual series resistance.

Referring to Fig. 1, *a* is the coupling, *b* and *c* are collector-rings for receiving and returning the magnetization current. *v* is the adjustable series resistance, which, on being adjusted to a higher resistance, imparts a high tension to the magnetization current in order to obtain rapid magnetization. *w₁* is the adjustable parallel resistance for the coupling 1, operative in case for instance a heavy torque is transmitted such as occurs during the cutting stroke of planing machines, *w₂* the similar resistance for coupling 2, operative in case for instance a light torque is transmitted, such as occurs during the idle return stroke of the planer. By in-

- creasing the parallel resistance, the time required for the diminution of the magnetism is reduced. u is the change-over switch, which is shifted, at the points of contact x , 5 y , z , to the left (arrow p_1) for the heavy torque, to the right (arrow p_2) for the light torque. n is the current supply system, n_1 being one, n_2 the other conductor. With the coupling cut-in for the heavy torque, the 10 path of current is as follows: The current passes from n_1 over fuse S_2 through parts of series-resistance v to collector-ring b , magnet coil a , ring c , through the change-over switch u to the contact piece y and now 15 back into the other conductor n_2 .

In Fig. 2 another modification is represented, showing the additional feature that the series resistance is divided into two separate sections, v_1 being a series resistance used 20 for heavy torques and v_2 being a series resistance for light torques, whereby it is possible to reduce or increase the time re-

quired for magnetization for both movements according to the different conditions.

A cut out d is inserted into the return line, 25 which permits the circuit to be opened at will.

The same reference letters are employed to indicate corresponding parts in Figs. 1 and 2. 30

I claim:

Device for correctly and rapidly changing over electromagnetic couplings, comprising magnetic coils, regulating resistances connected in parallel to the magnetic coils 35 for varying the time required for the magnetization to decrease, and regulating resistances in series to the magnetic coils for varying the time required for the magnetization to increase, for the purpose of controlling the starting moment of the changing over of the coupling.

In testimony whereof I affix my signature.

KARL MELLER.
